UNITED STATES PATENT OFFICE.

ALBERT F. GEORGE, OF KANSAS CITY, MISSOURI, ASSIGNOR OF ONE-HALF
TO JOSEPH H. FINK, OF SAME PLACE.

WINDMILL.

SPECIFICATION forming part of Letters Patent No. 508,009, dated November 7, 1893.

Application filed November 21, 1892. Serial No. 452,645. (No model.)

To all whom it may concern:

Be it known that I, ALBERT F. GEORGE, a citizen of the United States, residing at Kansas City, in the county of Jackson and State 5 of Missouri, have invented certain new and useful Improvements in Windmills, of which the following is a specification, reference being had therein to the accompanying drawings.

10. My invention relates to improvements in windmills.

The object of my invention is to provide a windmill with two or more concentric wheels each wheel having an independent connection 15 with the main or driving shaft.

My invention is adapted to be used with vertical or horizontal windmills.

In the accompanying drawings, I have shown my invention applied in both styles.

20. My invention is in accordance with the well known philosophical principle of a small wheel having the capacity for more rapid movement than a larger wheel both having the same wind pressure.

25. More specifically stated, my invention consists in mounting two concentric wheels upon the same shaft, gearing the inner wheel to the main shaft and gearing the outer wheel independently of the other wheel to the driving shaft.

In the accompanying drawings, illustrative of my invention, similar numerals of reference indicate similar parts.

Figure I represents a vertical sectional view 35 of my invention as applied to a vertical windmill. For clearness, only single opposite vanes are shown on each wheel. Fig. II represents a front view of the two wheels shown in Fig. I. Fig. III represents a vertical sectional view of a horizontal mill provided 40 with feathering vanes or blades and constructed in accordance with the principles of my invention. In this view the wind's direction is in the line of sight and for clearness the rear vanes and shafts are removed. Fig. IV represents a front detail view of the transferring gearing. Fig. V represents a side elevation of the parts shown in Fig. IV. Fig. VI represents a plan view of the horizontal 45 windmill. In this view the guy ropes and supporting posts are removed. The arrow in

this view indicates the direction of the wind, and the horizontal arms or shafts are in a vertical line with each other.

Referring to Figs. I and II, 1 indicates the 55 ordinary supporting stand; 2, indicates the base upon which the said stand is secured; 3, indicates a pivot socket secured upon the base 2; 4, indicates a vertical shaft pivoted in an opening in the socket 3, and provided 60 at its upper end with a bevel gear 5, which meshes into a bevel gear 6, movably mounted upon a horizontal shaft 7. 8, indicates a hub movably mounted upon said shaft 7, and secured to the bevel gear 6, in any suitable 65 manner. Secured upon the periphery of the hub 8, is a metallic ring 9, provided with a series of radial openings into which are fitted securely radial spokes 10. A metallic ring 11, provided with radial openings, is secured 70 upon the outer ends of the spokes 10. Vanes 12, are secured at the proper angle to and between the metallic rings 9, and 11. Securely fastened upon the shaft 7, and to the right of hub 8, is a hub 13, provided with a flange 14, 75 secured at its outer end. A metallic ring 15, is secured upon the periphery of the hub 13, and is provided with a series of openings into which are secured shouldered radial spokes 16. A metallic ring 17, is provided with 80 openings into which are fitted and secured the outer shouldered ends of the spokes 16. A metallic ring 18, is provided with openings corresponding in number and position to the spokes 16, which pass through said opening. The ring 18, is mounted upon the spokes at 85 about the same distance from the center shaft as the ring 11. Vanes 19, are secured between the rings 17, and 18, at the proper angle. The location of the vanes 12, and 19, with respect to each other, is best illustrated 90 in Fig. 2. I do not limit myself however, to this exact method of construction of the wind-wheels as any ordinary construction would answer. It is necessary however, to fully carry out the spirit of my invention, to mount the independent wheels so that the outer vanes do not overlap the vanes of the inner wheel. Brace rods 20, are secured at their ends to the flange 14, and the ring 18, respectively. 95 A head block 21, whose general form is a horizontal cylinder, is provided with a horizon-

tal longitudinal opening within which is movably mounted the shaft 7. The cylinder 21, is provided with a round, downward projection 22, fitted into a vertical opening in the 5 upper end of shaft 4 upon which the head block 21, rests and is circumferentially movable. A strap 23, surrounding the head block 21, is provided with an opening in its lower side into which is fitted the shaft 4. The upper 10 end of shaft 4, is provided with a flange 24, located between the head block 21, and the strap 23. This flange in connection with the ring strap 23, prevents any upward movement of the head block. A tail piece or guiding vane 25, is secured upon a horizontal arm 26, which in turn is secured to the top of the head block 21. A bevel gear 27, is firmly secured upon the left end of shaft 7, and meshes into a vertical bevel gear 28, movably mounted 15 upon a short shaft or projection 29, secured to a dependent projection 30, extending downward from the head block 21. Said bevel gear 28, meshes into a horizontal bevel gear 31, which is rigidly secured to the upper 20 end of a vertical sleeve 32, which is movably mounted upon the vertical shaft 4, and has one bearing within a central opening in the platform 33, and a bearing at its lower end upon an enlargement 34, of the shaft 4. Secured to the lower end of sleeve 32, is a 25 horizontal bevel gear 35, which meshes into a vertical bevel gear 36, movably mounted upon a horizontal sleeve 37, which in turn is mounted upon a horizontal main or driving shaft 38, and movable thereon. Secured at any point upon the shaft 4, but preferably as shown in the drawings, upon the projection 34, is a horizontal bevel gear 39, which meshes into a vertical bevel gear movably 30 mounted upon the right end of the sleeve 37. A pawl 41, is pivoted upon the rear side of the bevel gear 40, and engages with the teeth of a ratchet wheel 42, secured upon the sleeve 37. A pawl 43, is pivoted to the rear side of 35 bevel gear 36, and engages with the teeth of a ratchet wheel 44, secured upon the sleeve 37. A vertical brace 45, is secured upon the base 2, and is provided with an opening in which the horizontal shaft 38, is journaled. An 40 other vertical brace 46, is secured to the base 2, and is provided with an opening near its top which serves as a bearing for the sleeve 37. A washer 47, is secured upon the sleeve 37, to the right of the support or brace 46. 45 The following is a description of a clutch mechanism for communicating motion from the sleeve 37, to the shaft 38:—To the left of the support 46, is a sleeve 48, longitudinally movable upon the sleeve 37. A slot 49, is provided in the upper side of the sleeve 48. A pin 50, is secured to the sleeve 37, and engages in the slot 49, and thus prevents the sleeve 48, from rotating upon the sleeve 37, while permitting a lengthwise motion thereon. A projection 52, on the left end of the sleeve 48, is adapted to engage with the pin 53, secured to the shaft 38. A coil spring 54,

surrounds the sleeve 37, and is placed to the right of the sleeve 48, and to the left of the support 46. An L-shaped lever 55, is secured 70 to a transverse rod 56, which has bearings provided for it in a U-shaped support 57, secured upon the support 46. The vertical leg of the lever 55, is provided with bifurcated ends properly curved to fit into a groove 58, 75 encircling the sleeve 48. The horizontal leg of the lever has secured to it a cord 59.

I will now proceed to describe the operation of this form of my invention:—When the wind strikes against the face of the wheel, 80 the vanes 12, and 19, being in this instance set in the same direction both wheels will rotate, say to the right. This will cause the gear 40, which is connected to the inner wheel, to rotate to the right also. The ratchet pawl 85 41, engages with the ratchet wheel 42, and turns the sleeve 37, to the right with the same velocity that the smaller wheel is rotating, providing that the bevel gears are miter gears, as shown in this instance. The outer wheel 90 40, rotating to the right and being secured to the shaft 7, causes the gear 27, and the gear 31, through the intermediate gear 28, to also rotate to the right. The gear 31, being secured to the sleeve 32, causes said sleeve to rotate to 95 the right and also the gear 36, through the intermediacy of the gear 35. The proportions in size of the gears 27, 28, 31, 35, and 36, are such that, in this instance, the gear 36, will perform two revolutions to the one of the larger wind-wheel. The ratchet pawl 43, being pivoted to the gear wheel 36, and engaging with the teeth of the ratchet wheel 44, which is secured upon the sleeve 37, will tend to rotate the sleeve 37, to the right. The clutch sleeve 48, through 100 its projection 52, being normally in line of rotation with the pin 53, secured to the shaft 38, by reason of the tension of the coil spring 54, will cause said shaft 38, to revolve in the direction and with the sleeve 37, when said 105 sleeve 37, is revolved. If, for any reason, it is found desirable to release the shaft 38, from engagement with the clutch while the windmill is running, the cord 59, is drawn down and held. This rocks the lever 55, and 110 through its bifurcated leg causes the sleeve 48, to be forced backward against the pressure of the coil spring 54, thus releasing the pin 53, from engagement with the projection 52, of the clutch sleeve. When it is desired to 115 again start the shaft 38, in rotation, the cord 59, is released and the coil spring 54, forces the sleeve 48, together with its projection 52, into a position for re-engagement with the pin 53, of the shaft 38. It has been demonstrated by actual experiment that when the areas of the concentric wheels are equal the inner wheel moves at substantially double the rate of rotation of the outer wheel. However, the outer wheel is provided with greater 120 power by reason of its longer leverage, and to make the wheels exert substantially the same amount of power upon the horizontal sleeve 37, the gearing connected with the

outer wheel must be so proportioned that the gear 36, and 40, revolve at approximately the same rate of speed. If, for any reason the gear 40, revolves at any one time more rapidly than the gear 36, the ratchet wheel 44, will slip under the pawl 43. This will have a tendency to throw the work upon the inner wheel. The outer wheel being relieved will increase its velocity and soon resume its share of the work. When it is desired to have the wheels move in opposite directions and still have the power from each exerted upon the sleeve 37, in the same direction, the bevel gear 28, is omitted and the gear 27, is caused to mesh with the gear 31, the shaft 4, being shortened at its upper end and the face of the gear 27, reversed. By reversing the slant of either set of vanes 12, or 19, to that shown, an opposite rotation in the wheel to that heretofore indicated will be obtained.

The following is a description of the horizontal windmill provided with feathering blades and constructed in accordance with the principles of my invention:—100, indicates a vertical shaft provided with a bearing in the base 101, and a shouldered upper end fitted with a collar 102, which is connected by guy ropes 103, with upright posts 104, placed in the ground at the lower end or secured to the base 101. Secured near the upper end upon the shaft 100, is a head block 105. Into horizontal openings through said head block, are secured horizontal tubes 106, projecting each side of the vertical shaft 100. Secured within said tubes 106, are tubes 107, projecting at each end beyond said tube 106, and provided on its upper sides with a perforated projection at each end 108. Upwardly extending projections 109, from the head block 105, are connected respectively by braces 110; these braces serve to support the outer end of the tubes 107. Movably mounted within said tube 107, is a rock shaft 111, which extends at each end beyond the ends of the tube 107, on each side of the vertical shaft 100. Hinged to each end of shaft 111, is a dependent vane 112. The vane 112, is held in a vertical position when before the wind by a U-shaped spring 113, placed behind the vane and secured at its upper ends to the shaft 111. When the wind pressure is sufficiently great the spring backing 113, gives thus relieving the pressure upon the vane and preventing the liability of damage due to excessive speed. A pin 114, secured in the shaft 111, and so placed in a slot in the hinge of the vane as to come in contact with the hinge of the vane, serves as a stop which prevents the backward flapping of the vane upon the shaft 111. A pin 115, secured in each end of the shaft 111, in such a position as to be in a notch properly cut in each end of the tube 107, serves to prevent the shaft 111, from revolving more than a quarter of a circle. A head block 116, similar to head block 105, and having similar horizontal openings, has secured within said opening horizontal tubes

117, similar to the horizontal tubes 107, and provided with projections upon the upper side at each end 108, connected by braces 110, 70 with projections 109, upon the upper side of the head block 116. A shaft 118, similar to the shaft 111, has hinged thereto and dependent therefrom at each end a vane 119. A U-shaped spring 120, and similar to spring 75 113, is fastened at its upper ends upon each side of the vane 119, to each end of the shaft 118. Pins 114, and 115, are secured in and to the shaft 118, in the same manner and for the same purpose as described in connection 80 with the shaft 111. The head block 116, is rigidly secured to a vertical tube 121, mounted upon the vertical shaft 100, and having a bearing at its lower end to a horizontal bevel gear 122, secured to the vertical shaft 100, 85 near its lower end. Secured to the sleeve 121, near its center, is a head block 123, which has openings corresponding to the openings in the head blocks 105, 116, in which are pivoted at their centers horizontal shafts 90 124. A projection 125, extends outwardly from each side of the head blocks 123, is in line with and serves as a stop against which the pin 115, in the shaft 124, strikes. Hinged to each end of the shaft 124, is a vane 127, 95 provided with a U-shaped spring 128, secured to the shaft 124, in the same manner as spring 113, is secured to shaft 111. A pin 114, is secured in each end of the shaft 124, in the same manner and for the same purpose as 100 with shaft 111. A head block 129, secured upon the upper end of a sleeve 130, is of the same construction as head block 123, is provided with similar openings within which shafts 131, are pivoted at their centers. Vanes 105 132, similar to vanes 127, are hinged upon each side of the shaft 131, and are provided with U-shaped springs which serve as a backing and are secured at their upper ends to the shaft 131, in the same manner and for the same purpose as heretofore described with relation to the other U-shaped springs. A head block 134, is secured upon the upper end of a sleeve 135, movably mounted upon the sleeve 121, and provided with a bearing 110 at its lower end upon the flat surface of a flat bevel gear 136, secured to the lower end of tube 121. Tube or sleeve 130, is provided with a bearing at its lower end upon the flat surface of the head block 123. Secured to 115 the lower end of sleeve 135, is a horizontal beveled gear 137. Head block 134, is provided with openings within which are movably fitted rock shafts 138, provided at their ends with hinged vanes 139, and U-shaped springs 140, stop pins 115, and 114, as heretofore described with relation to the other rock shaft, vanes and springs. Secured to the lower end of sleeve 130, is a crown gear wheel facing downward. Secured to the upper end of sleeve 120 135, is a crown gear wheel 142, of the same size as crown gear wheel 141, with which it is connected by means of spur gears 143, and 144, which mesh together and into the crown

gears and are pivoted respectively upon pins 145, and 146, rigidly secured to the head block 123. Meshing respectively with the gear wheels 122, 126, 137, are vertical bevel gear wheels 147, 148, and 149, movably mounted upon a horizontal sleeve 37. Ratchet pawls 150, 151, 152, are pivoted respectively to the rear side of bevel gears 147, 148, 149, and engage respectively with the ratchet wheels 153, 154, and 155, which are rigidly secured to the sleeve 156. Mounted within the sleeve 156, is a horizontal driving shaft 157, revoluble within the sleeve. A support 158, is provided with an opening at its upper side 15 within which is pivoted the driving shaft 157, at its right end. A support 159, secured to the base 101, is provided also with an opening at its top in which is journaled the sleeve 156. The clutch mechanism is similar to that 20 shown in Fig. 1. The vanes upon the ends of each rock shaft are mounted upon said rock shaft at right angles one to the other. This is true also of the stop pins, which are secured in the outer ends of the rock shafts. 25 My horizontal wind mill operates as follows: When the wind strikes the face of the vane 112, it forces said vane into a vertical position and against the U-shaped spring 113, and causes the shaft 111, and head block 105, 30 together with the vertical shaft 100, to revolve, say to the right, as viewed in Fig. 6. This causes the bevel gear 147, to revolve toward the left, carrying with it the pawl 150, which engaging with the ratchet wheel 153, 35 causes it and the sleeve 156, to revolve also toward the left. The vanes all take a position similar to that of vane 112, when in such position as to be carried ahead of the wind. At the same time the vane on one side of a 40 shaft is forced into a vertical position. The wind striking against the vane on the other end of said shaft assists in rocking the shaft a quarter of a circle and causes the vane which is coming against the wind to assume 45 a horizontal position, as shown in Fig. 6. When the wind strikes the vanes 119, the head block 116, together with the vertical sleeve 121, to which it is secured, are caused to revolve to the right, thus revolving to the 50 left vertical bevel gear wheels 148, through the intermediacy of bevel gear 136. Pawl 151, pivoted to said bevel gear 148, engages the teeth of ratchet 154, and tends to revolve it and the sleeve 156, toward the left. The same 55 action takes place with reference to head block 123, which is also rigidly secured to the vertical sleeve 121. When the vanes 132 are caused to revolve, the head block 129, together with the vertical sleeve 130, to which it is secured, and the crown wheel 141, also secured to the sleeve 130, are caused to revolve toward the right and through the gear wheels 143, 144, cause the crown wheel 142, to also revolve toward the right, as viewed in Fig. 6, 60 carrying with it sleeve 135, and bevel gear 137, thus imparting rotation toward the left of bevel gear 149. Ratchet pawl 152, being thus

carried to the left and engaging with the ratchet wheel 155, tends to revolve the ratchet wheel and the sleeve 156, to which it is secured, toward the left. It will be seen that all of the gears 147, 148, and 149, are caused to revolve in a like direction, and in case of one revolving more rapidly than the other two, it can do so independently of the other, the only effect being that the ratchet wheels slip around under their pawls, and one set of windwheels is not held back by any of the others but acts independently. The inner wheels with their vanes, being smaller, travel 80 more rapidly than the outer ones but not having the same leverage do not exert as much power as the outer wheels during a complete revolution, so that to even up the power applied to the sleeve 156, by the several wheels, 85 the outer wheels are so geared to their respective gear wheels on the sleeve 156, as to produce a substantially uniform motion or rate of rotation of the several bevel gears mounted upon the horizontal sleeve 156. 90

It will be noted that in carrying out my invention it is not essential to mount the driving ratchets upon a sleeve 156, but they may be secured directly to the driving shaft, the only reason that I have in showing them 95 mounted upon the sleeve is to show a means of stopping the rotation of the driving shaft without stopping the rotation of the windmill.

Various other means, common in clutch 100 mechanism, may be used without departing from the spirit of my invention.

Having described my invention, what I claim, and desire to secure by Letters Patent, is—

1. In a windmill the combination of two or more concentric wind wheels, of a driving shaft means for independently establishing and disestablishing a driving connection between each wind wheel and the driving shaft 110 with each of said windwheels, suitable supporting mechanism, and means for disengaging revoluble connection between the windwheels and driving shaft, substantially as described. 115

2. In a windmill, the combination with the driving shaft, of two windwheels independent one from the other, means for independently establishing and disestablishing a driving connection between each wind wheel and the driving shaft, and suitable supporting mechanism, substantially as described. 120

3. In a windmill, the combination with the driving shaft, of two windwheels independent one from the other, mechanism for independently establishing and disestablishing a driving connection between each wind wheel and the driving shaft, suitable supporting mechanism, and means for releasing the connecting mechanism from the driving shaft, 125 substantially as described. 130

4. In a windmill, the combination with the driving shaft, of two or more concentric windwheels independent of each other, mechan-

ism for independently establishing and dis-establishing a driving connection between each wind wheel and the driving shaft, and suitable supporting mechanism, substantially as described.

5. In a windmill, the combination with the driving shaft, of two or more windwheels independently mounted upon a common shaft, means for independently establishing and disestablishing a driving connection between each wind wheel and the driving shaft, and suitable supporting mechanism, substantially as described.

6. In a windmill, the combination with the driving shaft, of two or more windwheels independently mounted upon a common shaft, means for independently establishing and disestablishing a driving connection between each wind wheel and the driving shaft, suitable supporting mechanism, and means for releasing the driving shaft from revoluble connection with the windwheels, substantially as described.

7. In a windmill, the combination with the driving shaft, of two or more independent windwheels, means for independently establishing and disestablishing a driving connection between each wind wheel and the driving shaft, commutative mechanism for applying the power of the windwheels to the driving shaft in a like direction, and suitable supporting mechanism, substantially as described.

8. In a windmill, the combination with a driving shaft, of two or more independent windwheels mounted upon a common shaft, means for independently establishing and disestablishing a driving connection between each windwheel and the driving shaft, commutative mechanism for applying the power of the wheels to the driving shaft in a like direction, substantially as described.

9. In a windmill, the combination with the driving shaft, of two or more independent windwheels, a vertical shaft connected by gearing with one of the windwheels, a vertical tube inclosing said vertical shaft and connected by gearing with the other windwheel, and means for connecting the vertical tube and the vertical shaft independently with the

driving shaft, and suitable supporting mechanism, substantially as described.

10. In a windmill, the combination with the driving shaft, of two independent windwheels concentrically mounted upon a common shaft, a vertical shaft connected by gearing with one of the windwheels, a vertical tube inclosing said vertical shaft, and connected by gearing with the outer windwheel, means for connecting the vertical tube and the vertical shaft independently with the driving shaft, and suitable supporting mechanism substantially as described.

11. In a windmill, the combination with the driving shaft, of two independent windwheels, a vertical shaft connected by gearing with one of the windwheels, a tube inclosing said vertical shaft, and connected by gearing with the other windwheel, means for connecting the vertical tube and shaft independently with the driving shaft, suitable supporting mechanism and means for disengaging revoluble connection between the vertical tube and shaft and the driving shaft, substantially as described.

12. In a windmill, the combination with the driving shaft, of two or more independent windwheels, a vertical shaft connected with one windwheel, a tube inclosing said shaft and connected with the other windwheel, commutative gearing connecting the windwheels and vertical shaft and tube, means for connecting said tube and shaft and the driving shaft, and suitable supporting mechanism, substantially as described.

13. In a windmill, the combination with the driving shaft, of a windwheel mounted upon a vertical shaft, a tube inclosing said shaft, another windwheel mounted upon said vertical tube, means for connecting the vertical tube and shaft, with the driving shaft, and suitable supporting mechanism, substantially as described.

In testimony whereof I affix my signature in presence of two witnesses.

ALBERT F. GEORGE.
